UNITED STATES PATENT OFFICE.

ANNA V. BENDER, OF COLUMBUS, OHIO.

DESIGN FOR AN IMITATION CANDLE FOR ELECTRIC-LIGHT FIXTURES.

Application filed January 10, 1923. Serial No. 4,854. Term of patent 7 years.

To all whom it may concern:

Be it known that I, ANNA V. BENDER, a citizen of the United States, residing at Columbus, in the county of Franklin and State of Ohio, have invented a new, original, and ornamental Design for Imitation Candle for Electric-Light Fixtures, of which the following is a specification, reference being had to the accompanying drawing, forming part thereof.

Figure 1 is a top plan view of an imitation candle for electric light fixtures, showing my new design, and

Figure 2 is a side elevation of the same.

I claim:

The ornamental design for an imitation candle for electric-light fixtures, as shown.

ANNA V. BENDER.
